US0D1065117S

(12) **United States Design Patent** (10) Patent No.: **US D1,065,117 S**
(45) Date of Patent: ** Mar. 4, 2025

(54) **SELF-POWERED WIRELESS SWITCH**

(71) Applicant: **Eaton Intelligent Power Limited**,
Dublin (IE)

(72) Inventors: **Alex Zhuang**, Shanghai (CN); **George Zhang**, Shanghai (CN); **Erik Jeffrey Gouhl**, Fayetteville, GA (US); **Harry Zhang**, Shanghai (CN); **Andrew Yang**, Jiangsu (CN); **Darron Kirby Lacey**, Peachtree City, GA (US); **Tom Xiong**, Shanghai (CN)

(73) Assignee: **EATON INTELLIGENT POWER LIMITED**, Dublin (IE)

(**) Term: **15 Years**

(21) Appl. No.: **29/827,919**

(22) Filed: **Feb. 23, 2022**

Related U.S. Application Data

(62) Division of application No. 29/780,837, filed on Apr. 27, 2021, now Pat. No. Des. 947,798, which is a division of application No. 29/684,572, filed on Mar. 22, 2019, now Pat. No. Des. 920,932, which is a division of application No. 29/593,417, filed on Feb. 8, 2017, now Pat. No. Des. 848,958.

CLAIM

The ornamental design for a self-powered wireless switch as shown and described.

DESCRIPTION

FIG. 1 is a top, side perspective view of the self-powered switch showing our design;

FIG. 2 is a side view thereof;

FIG. 3 is an opposing side view thereof;

FIG. 4 is an end view thereof;

FIG. 5 is an opposing end view thereof;

FIG. 6 is a top view thereof; and,

FIG. 7 is a bottom view thereof.

The broken lines in the drawings depict portions that form no part of the claimed design.
